UNITED STATES PATENT OFFICE

2,550,882

HOIST SAFETY VALVE

Frederick W. Sturm and Ross H. Arnold, Fort Wayne, Ind., assignors to The Wayne Pump Company, Fort Wayne, Ind., a corporation of Maryland

Application March 19, 1947, Serial No. 735,700

9 Claims. (Cl. 121—46)

1

This invention pertains to lifts or hoists and the construction thereof including lift safety valves for full hydraulic and semi-hydraulic hoists, the valves insuring that a proper amount of fluid will be kept in parts of the hoist system for proper and safe operation of the hoists.

It is an object of this invention to provide a lift utilizing any desired form of superstructure wherein in the operating mechanism there are few parts to wear, and such wearing parts are disposed so that maintenance operations can be easily and simply performed.

Another object of the invention is to provide a lift which is simple to install and maintain and wherein safety means is provided to insure that the proper amount of operating fluid is maintained in the lift system for proper and safe operation.

Another object of the invention is to provide safety mechanism for lifts which is operative under predetermined conditions to prevent operation of the lift to raised position, but will permit the lift to be lowered should trouble occur such as that due to leaking packing or pipe line.

Another object of the invention is to provide a lift wherein safety mechanism is provided which will permit the lift being rendered inoperative should a failure occur when the lift is in lowered position, and will permit the lift to be lowered by normal operation if trouble occurs when the lift is in raised position.

Another object of the invention is to provide safety mechanism for lifts which are applicable to lifts of either the full hydraulic or semi-hydraulic types.

Another object of the invention is to provide safety control mechanism for lifts operative upon predetermined failure to render the lifting mechanism of the lifts ineffective but which can be readily moved to inoperative position after the failure has been corrected.

Another object of the invention is to provide lift structure utilizing a fixed casing and a relatively movable ram, which may be rotated with respect to the casing, and wherein widely spaced bearings are provided for the ram.

Another object of the invention is to provide a lift construction wherein a relatively fixed casing and movable ram is provided and wherein fixed and movable bearings are provided for the ram.

With these and various other objects in view, the invention consists of certain novel features of construction and operation as will be more fully described and particularly pointed out in the specification, drawings and claims appended hereto.

In the drawings, which illustrate an embodiment of the device and wherein like reference characters are used to designate like parts:

2

Figure 1 is a sectional elevation through a semi-hydraulic hoist operating cylinder and piston embodying the invention, and showing a safety valve applied thereto;

5 Figure 2 is an enlarged, fragmentary sectional elevation through a portion of the piston head showing the application thereto of the safety valve shown in Figure 1;

10 Figure 3 is a sectional elevation of a full hydraulic hoist showing the operating tank for the piston, the operating tank being provided with the hoist safety valve; and

15 Figure 4 is an enlarged fragmentary sectional elevation of the hoist safety valve illustrated in Figure 3.

Referring first of all more particularly to the structure illustrated in Figure 1, the outer fixed cylinder or casing 10 is embedded in the ground 12 preferably so that a portion of the upper open 20 end of the casing 10 will project slightly above the ground level. The inside of the casing for at least a portion of its length from the lower end is machined to form a bearing surface 14, the length of the bearing surface depending upon the 25 lift, and the lower end of the casing 10 is closed by means of the head or lower closure 16. The head is provided with the recess or passage 18 communicating with the air supply pipe 20 which extends upwardly and is connected through the 30 manual control valve 22 to the pipe 24, which in turn is connected to a suitable source of air pressure. While "air" is referred to as the pressure supplying fluid, of course, it is understood that any other suitable operating fluid may be used.

35 The hollow, movable ram, piston or plunger 26 is mounted in the casing 10 and is provided with the lower closure 28, so disposed within the ram 26 that the lower end of the plunger forms a 40 flange or skirt 30, said flange being apertured as at 31 and provided with the lower bearing 32 having sliding engagement with the bearing surface 14 of the casing 10. The upper end of the casing 10 is closed by means of the upper guide bearing 45 34 which has bearing engagement with the ram 26 and is provided with the flange 36 overlying the flange 38 provided on the casing 10, whereby the flanges 36 and 38 may be connected together. The bearing 34 is provided with the 50 packing recess 40 adapted to receive suitable packing such as the chevron packing 42, the packing being retained by means of the closure plate 44 adapted to be secured to the flanges 36 and 38, which closure plate 44 may be provided with wiping means within the recess 46, or this may be a lubricant recess or groove. An upper wiper 48 and retaining plate or casting 50 is provided suitably secured to the flange 36.

55 Casing 14 and ram 26 are cylindrical and the 60 axes thereof coincides. The head 16 is provided

with the upstanding standpipe 52 communicating with the passage 18 and is so disposed that its axis coincides with the axes of the casing 14 and ram 26. The standpipe 52 extends through the closure 28, the opening in the closure 28 through which pipe 52 extends being sufficient to provide an oil passage 54, and other oil passages 56 are provided in the closure 28, the flow through the passages 56 being controlled by the valve disk 58 carried by the stem 60 fixed to closure 28.

An air eliminator, indicated generally at 62, communicates with the inside of the ram 26 through fitting 64 and pipe 66, said pipe extending to and being conveniently anchored in the stop ring 68, which is spaced from the lower bearing 32 a predetermined distance, and is adapted to contact the upper bearing 34 to limit the distance the ram may be raised.

The upper end of the standpipe 52 is secured as at 70 to the spring seat fitting 72 which in turn is connected as at 74 to the valve body housing 76. Housing 72 is provided with the spring seat 78 upon which the lower end of the poppet lifting spring 80 is disposed, the upper end being adapted to engage the guiding fins 82 of the poppet 84. The poppet is urged upwardly by means of the spring 80, and under conditions to be later described, is adapted to close the valve seat 86 provided on the housing 76. The poppet 84 is provided with the upwardly extending stem 88 which extends through a suitable guide 90 provided on the bracket 92 which extends within the downwardly directed flared flange 94 of the cap 96, when the ram is in lowermost position.

Cap 96 is secured as at 98 to the top closure 100 secured to the upper end of the plunger, the closure 100 being adapted to be connected by suitable cross bracing (not shown) to suitable rails, such as the drive-on or free wheel type where the hoist is used for automotive vehicles, and connected to any other type of support where the hoist is adapted for other uses. Types of hoist superstructure and the connections thereof to the ram are shown and described in application Serial No. 604,407, filed July 11, 1945 for Hoist. The cap 96 is provided with an opening plug 102 which may be removed for permitting access to stem 88 for manually depressing said stem.

Stem 88 is provided with the latch collar 104 which is adapted to have cooperative engagement with the latch member 106 of the latch 108. Latch 108 is pivoted as at 110 to the bracket 92 and is provided with the leg 112 adapted to be loosely engaged between nuts 114 and 116 provided on the float rod 118 to secure said leg to said rod. The float rod extends downwardly a predetermined distance through a passage 119 (which may be a bearing) and is provided with the float 120 slidably and loosely mounted around the standpipe 52, the position of the float being determined by the oil level in the ram 26. An oil gauge 122 is provided in the closure 100 for ascertaining the oil level in the plunger in the same manner that an oil gauge is used in ascertaining the oil level in an automobile engine crank case. The line 124 indicates the oil level within ram 26 when it is in its lowermost position. The gauge may also be marked with other marks 125 showing "Full" and "Low" levels and of course other marks may be applied as desired. While "oil" has been referred to as being the fluid in the casing and ram other suitable fluids of course can be used.

In the operation of the device, let it be as-

sumed that the oil level within the ram 26 is at its normal operating height, and the ram is in lowermost position (Figure 1). In that position the flange 30 acts as a lower stop by engaging the closure 16. With the oil level at its normal height, the float 120 will be urged upwardly so that the latch 108 will be urged in a clockwise direction as viewed in Figure 2. The collar 104, when the stem 88 is depressed, is engaged by the latch member 106 retaining the poppet 84 in open position. When it is desired to raise the ram, valve 22 is properly operated, admitting operating fluid, such as compressed air, through pipe 20, passage 18, standpipe 52 and through housing 76 to the space between the top of the oil in ram 26 and the closure 100. The oil will be forced downwardly through passages 54 and 56 to raise the plunger a predetermined amount such as until stop 68 engages bearing 34 or at some intermediate point as when the valve 22 is closed before the stop reaches the upper bearing. Release of the air pressure within the ram by operation of valve 22 will permit the oil between the casing and ram to flow through passage 54 into the ram to displace the air through housing 76 to permit the lowering of the ram.

After use, if the oil level should drop to a position where the float 120 is permitted to move downwardly too far, the downward movement of the float 120 will move the latch member 106 out of engagement with the collar 104 and the spring 80 will close the poppet 84. Should this occur while the ram is in raised or partially raised condition, it can still be lowered as the air pressure within ram 26, acting on the upper surface of valve 84, will overcome the force of spring 80 to open poppet valve 84 when valve 22 is positioned so as to release air pressure from within the ram. Oil can be supplied to the ram by removing the gauge 122 and using the opening as a fill opening, and when the oil is at its proper level, the gauge can be replaced closing the fill opening, the plug 102 (which may also be used as an oil fill opening) can be removed, and the stem 88 can be depressed to permit the poppet 84 to be locked open by engagement of the latch member 106 with the collar 104. The lift is then ready for normal raising and lowering operation.

Referring now to the full hydraulic type of lift or hoist illustrated in Figure 3, said lift comprises the outer fixed cylinder or casing 126 which is adapted to be fixed within the ground 128 with its upper end slightly above the ground, the casing being provided with the lower closure 130, the casing 126 being provided for at least a portion of its length with the bearing surface 132 for the lower bearing 134 provided on the depending flange or skirt 136 of the ram, piston or plunger 138. The lower end of the ram or plunger is closed by means of the lower closure member 140 whereby the flange or skirt 136 is defined, said skirt preferably being provided with the passages 142, and the ram being provided with the stop ring 144 disposed a predetermined distance above the lower bearing 134 and being adapted, in the uppermost position of the ram, to engage the undersurface of the upper bearing 146 disposed in the upper portion of the casing 126. In the lowermost position of the ram the skirt 136 acts as a lower stop by engaging the closure 130.

The bearing 146 is provided with the outwardly extending flange 148 overlying, and being adapted to be connected to, the flange 150 provided at the upper end of the casing 126. Upper bearing 146

is adapted to have bearing engagement with the ram and is provided with the packing recess 151 for the reception of suitable packing, such as the chevron packing 152. The packing is retained by the upper closure plate 154 secured to the flanges 148 and 150, and a wiper may be provided in recess 156 or this may be a lubricant recess or groove. A wiper 158 and upper retaining member 160 is provided, retaining member 160 being adapted to be connected to the flange 148.

The upper end of the ram 138 is provided with the closure 162 which is connected through suitable bracing (not shown) to the superstructure desired, as described above. In this construction it is noted that the operating fluid, such as oil, is retained only between the casing 126 and the ram 138. Operating tank 164 containing fluid preferably the same as in the casing, (such as the oil) is conveniently disposed with respect to the hoist and is provided with the pipe 166 extending from a point adjacent the bottom of the tank 164 upwardly, and being connected through the manual oil control valve 168 to the pipe 170, which is connected through oil control valve 172 to the casing 126, flow to and from the casing being permitted through the opening 174. The operating fluid is disposed within the casing 126 and in pipes 170 and 166 and in the operating tank 164 to a predetermined level, the level of the operating fluid necessary to raise the hoist to maximum height being indicated at 176, the lowest approximately safe oil level being indicated as at 178.

A removable calibrated gauge 180 is provided on the upper end of the tank operative in the same manner as gauge 122 to ascertain the oil level. It is desirable that the oil level be retained at a point higher than the line 176, being preferably retained at the high mark indicated by the line 182. The upper head 184 of the tank 164, through which pipe 166 extends, is provided with the valve body 186 threaded or otherwise secured as at 188 to the head 184, the top of the body 186 being closed by means of the threaded plug 190. The body 186 is provided with the valve seat 192 adapted to be controlled by the valve poppet 194, the poppet 194 being provided with the depending float rod 196 extending downwardly through bushing 198 disposed above the skirt 200 of the body 186, an air passage between the valve and tank being provided at 202.

The skirt 200 is provided with the depending float rod tube 204 provided with the vent holes 206 and within which is disposed the float 208 secured to the float rod 196 adjacent the lower end thereof. The upper end of the housing 186 above the poppet 194 is provided with the air inlet 210 adapted to be secured to a suitable source of fluid pressure, as air pressure, the supply of air to and from the inlet 202 being controlled by a suitable manually controlled air valve (not shown). Within the housing 186 there is provided a latch pivot 212 to which the latch member 214 is pivoted, the latch and pivot being so constructed and arranged that the free end of the latch tends to move (counterclockwise in Figure 4) into the path of the poppet 194, said latch having a reset lug 216.

When the oil level is sufficiently high, the float 208 is urged upwardly, urging the poppet 194 upwardly away from its seat 192. The plug 190 can be removed and the latch 214 moved to its dotted line position as illustrated in Figure 4, by depressing lug 216, thus permitting the poppet 194 to raise to a point where it is open and dis-

posed in the path of the latch, retaining the latch in its dotted line position. Operating air can then be supplied through the opening 210, passing downwardly past the valve seat 192 to the space between the oil and head 184 of the tank 164 through passages 202, forcing the oil through pipe 166, valve 168, assuming said valve to be open, through pipe 170 past valve 172 into the casing 126, causing raising movement of the ram 138.

Opposite operation of the air control valve will, of course, permit air pressure above the oil in the tank 164 to be released permitting downward movement of the ram 138. Should the oil level fall below a predetermined level, such as 178, the float 208 will move downwardly, moving the poppet 194 toward seat closing position, permitting the latch 214 to move to its latched position as shown in the full line position illustrated in Figure 4. In this full line position, the poppet 194 is closely adjacent its seat so that any air pressure supplied through the opening 210, will seat the poppet 194, preventing the pressure from reaching the oil in the operating tank 164. As before, downward movement of the ram would be permitted should the oil level fall, and should the ram be in a raised or partly raised position, as the air pressure above the oil in tank 164 would be permitted to bleed past the valve 194, due to the fact that the latch 214 is of such length as to permit a slight movement of the poppet 194 from seated position.

It is to be understood that this application is not to be limited by the exact embodiments of the device shown, which are merely by way of illustration and are not limited thereto, as various and other forms of the device will, of course, be apparent to those skilled in the art without departing from the spirit of the invention or the scope of the claims.

We claim:

1. Hoist construction comprising a cylinder, a ram mounted to reciprocate vertically within said cylinder, the upper portion of said ram being adapted to be provided with load supporting superstructure, said cylinder being adapted to contain a liquid, means for introducing fluid pressure above the level of the liquid in said cylinder, and means for preventing introduction of said fluid pressure into said cylinder when the level of the liquid is below a predetermined point the second named means including a normally open valve for controlling fluid flow to raise or lower the ram, means for causing the valve to close should the fluid level fall below the predetermined level, and means for holding said valve in closed position after it is once closed, said last named means being ineffective to close the valve when the fluid level is above the predetermined level and the valve is open.

2. Hoist construction comprising a cylinder, a ram mounted to reciprocate vertically within said cylinder, the upper portion of said ram being adapted to be provided with load supporting superstructure, said cylinder and said ram being adapted to contain a liquid, means for introducing fluid pressure above the level of the liquid in said ram, and means for preventing introduction of said fluid pressure into said ram when the level of the liquid is below a predetermined point, said last named means being movable to permit authorized escape of said fluid pressure on said liquid when said ram is in a raised position.

3. Hoist construction comprising a cylinder, a

ram mounted to reciprocate vertically within said cylinder, the upper portion of said ram being adapted to be provided with load supporting superstructure, said cylinder being adapted to contain a liquid, an operating tank connected to said cylinder and having liquid therein, means for introducing fluid pressure above the level of the liquid in said operating tank, and means for preventing introduction of said fluid pressure into said tank when the level of the liquid in the operating tank is below a predetermined point, said last named means being movable to permit authorized escape of said fluid pressure on said liquid when said ram is in a raised position.

4. Hoist construction comprising a cylinder, a ram mounted to reciprocate vertically within said cylinder, the upper portion of said ram being adapted to be provided with load supporting superstructure, said cylinder and said ram being adapted to contain a liquid, means for introducing fluid pressure above the level of the liquid in said ram and permitting release thereof, and means for preventing the introduction of said fluid pressure into said ram when the level of the liquid is below a predetermined point in said ram.

5. Hoist construction comprising a cylinder, a ram mounted to reciprocate vertically within said cylinder, the upper portion of said ram being adapted to be provided with load supporting superstructure, said cylinder and said ram being adapted to contain a liquid, means for introducing fluid pressure above the level of the liquid in said ram and permitting release thereof, and means for preventing the introduction of said fluid pressure into said ram when the level of the liquid is below a predetermined point in said ram, but permitting said fluid pressure to escape from the interior of said ram through said first named means when said ram is in a raised position.

6. Hoist construction comprising a cylinder, a ram mounted to reciprocate vertically within said cylinder, the upper portion of said ram being adapted to be provided with load supporting superstructure, said cylinder and said ram being adapted to contain a liquid, means for introducing fluid pressure above the level of the liquid in said ram, and means for preventing introduction of said fluid pressure into said ram when the level of the liquid is below a predetermined point.

7. In a hoist, the combination of an outer fixed casing, an inner slideable ram disposed to slide in said casing and having an upper end adapted to be provided with a load supporting superstructure, a closure for the lower end of said casing, a closure for the upper and lower ends of said ram, liquid disposed in said casing and ram, the ram lower closure being provided with an opening permitting communication between said casing and ram, means for supplying fluid pressure into said ram above the liquid level therein for raising said ram and exhausting fluid pressure to lower said ram, said means having a valve for controlling supply and exhaust of fluid pressure to and from said ram and provided with a latch member, a latch adapted to engage the latch member to hold the valve in open position to permit entrance of fluid pressure to said ram, a float in said ram connected to said latch in such a manner that when the liquid level is above a predetermined point the valve may be latched open, but when it falls to a point at or below said predetermined point the float unlatches the valve, and a resilient

member for closing the valve when the latch is in unlatched position and the liquid level is at or below said predetermined point.

8. In a hoist, the combination of an outer fixed casing, an inner slideable ram disposed to slide in said casing and having an upper end adapted to be provided with a load supporting superstructure, a closure for the lower end of said casing, a closure for lower end of said ram for preventing fluid access to said ram, liquid disposed in said casing around said ram, a liquid container connected to said casing and having liquid therein, means for supplying fluid pressure to said container above the level of liquid therein to thereby force the liquid from said container to said casing to raise said ram, said last named means including a housing having an opening to said container having a valve controlling said opening, said housing having a fluid pressure connection whereby said fluid pressure is supplied to or exhausted from said valve, a float in said container connected to said valve urging it to open or closed position as governed by the liquid level in said container, and a biased latch in said casing which prevents opening movement of said valve after the liquid level has fallen a predetermined amount until the level has been raised to a predetermined point and the latch moved to inoperative position where it is maintained by said valve until the liquid level falls a predetermined distance.

9. In a hoist, the combination of an outer fixed casing, an inner slideable ram disposed to slide in said casing and having an upper end adapted to be provided with a load supporting superstructure, liquid disposed between said casing and ram, valve means through which operating fluid regulates the amount of liquid disposed between said casing and ram for selectively raising or lowering said ram, means for rendering said valve means ineffective if the level of said fluid falls below a predetermined level, the second named means including a housing adapted to be connected to a source of operating fluid, said housing having a valve seat and normally open valve for seating on said seat, said valve in open position permitting flow of operating fluid to raise or lower the ram, said valve in closed position preventing flow of operating fluid to raise the ram, means for causing the valve to close should the liquid level fall below the predetermined level, said last named means including a member positively movable from one extreme position where the valve is closed to another extreme position where the valve is open, the last named means being ineffective to close the valve while the fluid level is above the predetermined level and the valve is open.

FREDERICK W. STURM.
